UNITED STATES PATENT OFFICE.

DAVID Y. WILSON, OF GUM TREE, PENNSYLVANIA.

RAILWAY-TIE AND FASTENER.

SPECIFICATION forming part of Letters Patent No. 445,326, dated January 27, 1891.

Application filed June 5, 1890. Serial No. 354,308. (No model.)

To all whom it may concern:

Be it known that I, DAVID Y. WILSON, a citizen of the United States, residing at Gum Tree, in the county of Chester and State of Pennsylvania, have invented certain new and useful Improvements in Railway-Ties and Fasteners, of which the following is so full and clear a description that it will enable others skilled in the art to which it appertains to make and use the same, reference being had to the accompanying drawings, in which—

Figure 1 is a top plan view of the tie and fastenings, and Fig. 2 is a vertical longitudinal sectional view of the same, taken on the line $x x$ of Fig. 1. Fig. 3 is a top plan of another form of a tie and fastenings. Fig. 4 is a vertical longitudinal sectional view of the same, taken on the line $x' x'$, Fig. 3. Fig. 5 is a plan view of one of the washer-blocks. Fig. 6 is a detail perspective view of the plug. Fig. 7 is a detail view of the key. Fig. 8 is a bottom plan of the polygonal washer-block. Fig. 9 is a plan view of a wooden plate, and Fig. 10 is a plan view of a felt plate or piece.

The invention consists in the novel construction to be hereinafter described, and particularly pointed out in the claims at the end of this specification.

In the accompanying drawings, A designates the tie, to which is adapted to be secured the rail G, and beneath which is placed a felt washer H, which is provided with a waterproofing, such as tar, pitch, resin, or crude oil; or a piece of wood may be similarly treated and used in place of the felt.

In Fig. 1 I show the tie provided with perforations C C, which are elongated at one end and have a slot G', which extends parallel with the line of the track, and which has at its end an elongated opening or slot which extends at right angles to the line of the slot G', and extending slightly beyond the line of the side of the slot G' at either side. In this T-shaped slot I place a bolt E, which is inserted through the enlarged end of the T-shaped hole and moved along till it rests in the end P of the slot. It is held in such position against lateral movement by a key S, which has a bifurcated lip S', which straddles the bolt, and at its opposite end it has a projecting head S², which is adapted to rest be-

tween the washer-block F and the flange of the rail R. The washer-block F has a raised platform J, which has straight sides 1 2 3 4 5 55 6, &c., each a distance from the opening in the block, which distance in each case differs from the distance from any other side to said opening. This enables me to readjust the block to compensate for wear and the natural working loose of the rail in its fastenings.

In Fig. 3 I show the tie having a hole C', which is provided with an elongated opening j, extending from the hole C' toward the seat for the rail, and extending at right angles to the line of the latter when in its natural position on the track. This opening is used with a fastening similar to the one shown in Figs. 1 and 2, with the exception that I use a plug k, which fits into the hole C and extends along 70 with the opening j a sufficient distance to hold the bolt in position. This plug k has an extending flange c, which prevents it from falling through the hole C' into the road-bed. The plug k is of a width approximately equal 75 to or less than the thickness of the tie. This form of plug and fastening is especially adapted for use in places where the road-bed immediately beneath the rail-fastening is practically solid and impenetrable at the 80 surface.

The washer-block F has beveled edges a a at the outer under sides, and in Fig. 4 it has a recess m at the junction of the raised portion and the main upper part of the block 85 proper. In this recess the cushion H fits to form a firm setting for the various devices which constitute the fastening.

I do not wish to be understood as limiting myself to the exact construction shown, as the 90 details may be varied at will without departing from the spirit of my invention.

The matter shown on Sheet 1 of the drawings is made the subject of another application filed by me in the United States Patent 95 Office, and bearing the Serial No. 340,718, and it is therefore disclaimed in this application.

Having described my invention, what I claim is—

1. A metallic tie-fastening consisting of a 100 tie having perforations which are extended from an enlarged portion, the extensions being narrower than the main perforation, in combination with a bolt, a cushioning for the rail,

a washer-block having a raised polygonal portion on its lower side and having beveled edges, and provided with recesses at the various sides for the reception of the edges of the cushioning, and a plug beneath the washer-block, all constructed and combined to operate substantially as described.

2. A metallic tie-fastening consisting of a tie having perforations which are extended from an enlarged portion, the extensions being narrower than the main perforation, in combination with a bolt, a cushioning for the rail, which is provided with a waterproofing preservative, a washer-block having a raised polygonal portion on its lower side and also having beveled edges, and provided with recesses at the various sides for the reception of the edges of the cushioning, and a plug beneath the washer-block, all constructed and combined to operate substantially as described.

3. A metallic tie-fastening consisting of a tie having perforations which are extended from an enlarged portion, the extensions being narrower than the main perforation and having an extending portion at the narrower end, which extends at right angles to the line of the track when in its operative position, in combination with a bolt, a cushioning for the rail, and a washer-block having a raised polygonal portion on its lower side and also having beveled edges, and provided with recesses at the various sides for the reception of the edges of the cushioning, and a plug beneath the washer-block, all constructed and

combined to operate substantially as described.

4. A metallic tie-fastening consisting of a tie having perforations which are extended from an enlarged portion, the extensions being narrower than the main perforation, made T shape at its narrower end, in combination with a bolt, a cushioning for the rail, a washer-block having a raised polygonal portion on its lower side and also having beveled edges, and provided with recesses at the various sides for the reception of the edges of the cushioning, and a plug beneath the washer-block, all constructed and combined to operate substantially as described.

5. A metallic tie-fastening consisting of a tie having perforations which are extended from an enlarged portion, the extensions being narrower than the main perforation, which is approximately flush with the under surface of the tie, in combination with a bolt, a cushioning for the rail, a washer-block having a raised polygonal portion on its lower side and also having beveled edges, and provided with recesses for the reception of the edges of the cushioning, and a plug beneath the washer-block, all constructed and combined to operate substantially as described.

In testimony whereof I affix my signature in the presence of two witnesses.

DAVID Y. WILSON.
